COMBINED SUSPENDED MIRROR AND LIGHT THEREFOR

De Anna L. Holton, 3806 Sycamore Drive,
Boise, Idaho 83703

Filed Jan. 14, 1970, Ser. No. 20,923

Term of patent 14 years

Int. Cl. D26—02; D28—03

U.S. Cl. D48—20

FIG. 1 is a top perspective view of the combined suspended mirror and light therefor embodying my new design with the mirror in a closed position.

FIG. 2 is a top perspective view thereof with the mirror in an open position.

FIG. 3 is a bottom perspective view thereof with the mirror in a closed position.

The sides of the mirror not disclosed are plane and unornamented.

I claim:

The ornamental design for a combined suspended mirror and light therefor, as shown and described.
